(57) CLAIM

The ornamental design for a face protector, as shown and described.

DESCRIPTION

FIG. 1 is a front perspective view of an embodiment of the face protector.

FIG. 2 is a front elevational view of the face protector.

FIG. 3 is a right side elevational view of the face protector.

FIG. 4 is a rear elevational view of the face protector.

FIG. 5 is a left side elevational view of the face protector.

FIG. 6 is a bottom plan view of the face protector; and,

FIG. 7 is a top plan view of the face protector.

The broken lines shown in FIGS. 1-7 are included for the purpose of illustrating environmental elements only and form no part of the claimed design.
